AXIAL FLOW COMPRESSORS

Charles Peter Langworthy Ricketts, Bristol, England, assignor, by mesne assignments, to Bristol Siddeley Engines Limited, Bristol, England, a British company

Filed Dec. 10, 1956, Ser. No. 627,395

Claims priority, application Great Britain Dec. 23, 1955
1 Claim. (Cl. 230—134)

This invention relates to axial flow compressors, and concerns the rotors of such compressors which rotors are of the kind comprising a plurality of blade-carrying discs, some at least of which are provided near their rims with an axially extending flange the end of which abuts the end of a similar flange or a face on an adjacent disc so as to form a disc-and-drum structure, and wherein some at least of the said flanges and the discs between which they extend constitute walls of separate chambers within the rotor. By "separate chambers" is to be understood chambers which are not in communication with one another except possibly by indeterminate incidental leakage paths between parts bounding the chambers.

According to the invention, in an axial flow compressor having a rotor of the kind described, there is provided in the rotor, for each of two or more of said separate chambers which are adjacent to one another, passage means communicating the chamber with the working fluid passage of the compressor so that the pressure in the chamber will at all times be dependent upon the pressure in the working fluid passage at the place therein with which the passage means communicates.

The provision in the rotor of such passage means enables the pressures which will occur in said adjacent chambers during the working of the compressor, and so the resultant endwise pressure loadings on the discs, bounding said adjacent chambers to be predetermined accurately, so that suitable provision can be made for resisting deflection of these discs under these loadings. Preferably each of said adjacent chambers communicates with the working fluid passage of the compressor between the rows of blades carried by the adjacent discs constituting walls of the chamber. This arrangement ensures the grading of the pressures in adjacent chambers so that the whole or a major part of the load does not fall on any one disc.

The invention also includes the provision of means for resisting the deflection of such discs as may be subjected to endwise loading as above described.

In a preferred arrangement according to the invention, the rotor comprises an intermediate group of flat blade-carrying discs each of which is provided on each side near its rim with a flange extending axially of the rotor, and two further blade-carrying discs one at each end of said group, each of which has near its rim on the side facing said intermediate group of discs a flange extending axially of the rotor, all said flanges being cylindrical and of the same diameter and abutting one another at interfaces which are common for each adjacent pair of flanges, and said passage means comprises, at each said common interface, a slot provided in at least one of the abutting pair of flanges, the slot providing a passage between the inside and outside of the disc-and-drum structure constituted by said discs and flanges.

All the said flanged blade-carrying discs may be secured together by a plurality of bolts extending axially through all the flanges, and the flanges may be located relatively to one another at the said common interfaces by axially disposed dowels and sockets.

In an arrangement of the kind described in the next but one preceding paragraph, said passage means may, according to a feature of the invention, comprise, at each said common interface, a plurality of flat-bottomed slots

2

in the abutment face of at least one of the flanges abutting at the interface, the slots being spaced around the interface and serving both as passages between the inside and the outside of the disc-and-drum structure and as openings for the reception of a wedge-shaped tool for the purpose of separating the flanges abutting at the interface during disassembly of the rotor.

An axial flow compressor rotor in accordance with the present invention will now be described by way of example with reference to the accompanying drawings in which:

FIGURES 1a and 1b together show the rotor in cross-sectional side elevation, these figures joining together along the vertical chain-dot lines on the right and left hand side respectively of FIGURES 1a and 1b to show the whole of the rotor,

FIGURE 2 is a scrap sectional view corresponding to the lines 2—2 in FIGURES 1a and 1b, and

FIGURE 3 is a view in the direction of the arrow 3 in FIGURE 2.

The compressor rotor which is about to be described forms part of a rotor assembly for a gas turbine engine, the rotor assembly also including a turbine rotor. The compressor rotor and the turbine rotor (not shown) are rigidly coupled together by an intermediate shaft 60, part only of which is shown, to form a single rotor assembly, and the rotor assembly is supported on two bearings, one forward of the compressor rotor and the other rearward of the turbine rotor.

The compressor rotor comprises seven discs upon each of which a row of blades 16 is mounted. The end two blade-carrying discs 11 and 12 at the low pressure end of the compressor rotor are frusto-conical in shape and converge towards one another from the peripheral radius 35 of the drum structure of the rotor to an inner peripheral radius at which they are connected together. The discs 11 and 12 have central openings 38. Near their inner peripheries the discs 11 and 12 are provided with abutting parts in the form of cylindrical axial extensions 11b and 12b constituting spacing members for the discs 11 and 12 proper. In this region the discs 11 and 12 are connected together and also to a hollow stepped cylindrical stub-shaft or spigot 13 extending forwardly thereof, by a number of nuts 15 and bolts 16 which pass through axially-extending holes 17 and 18 in the discs 11 and 12 respectively, and through corresponding holes 19 in a flange 20 integral with the spigot 13. The inner races of a double ball bearing 14 are mounted on the spigot 13. This is the front supporting bearing of the rotor assembly referred to above.

The third, fourth and fifth blade-carrying discs 21, 22 and 23 are flat, that is to say they are symmetrical on each side of a flat central transverse plane. The sixth and seventh blade-carrying discs at the high pressure end 55 of the compressor rotor are dished towards one another and comprise central flat portions 24 and 25 in abutting relation, and outer frusto-conical portions 26 and 27 diverging from one another.

Disc 12 is provided with a rearwardly extending cylindrical flange 12a near its periphery, while each of the flat discs 21, 22 and 23 are provided with similar cylindrical flanges 21a, 22a, and 23a extending forwardly and 21b, 22b and 23b extending rearwardly. Disc 24 is provided with a forwardly extending cylindrical flange 24a.

All these flanges are of the same diameter and meet at common interfaces 61, 62, 63 and 64 to form a disc-and-drum structure which is held together by a number of bolts 29 and nuts 31, the bolts passing through circumferentially spaced axially extending holes, such as 28, in the flanges. These bolts 29 are provided at each end and in the region of each common interface with portions 32 which are a close fit in the holes 28, the intermediate

portions of the bolts being reduced to a clearance diameter. For additionally locating the flanges at the common interfaces a number of dowels 65 are inserted in circumferentially spaced holes 66 in the flanges, the holes extending axially of the rotor.

The blades 10 carried by the discs 11, 12, 21, 22, 23, 24 and 25 are provided with "fir tree" roots 33 which fit into corresponding "fir tree" slots 34 in the rim of each disc in known manner. Suitably flanged rings such as 35 are disposed between the peripheries of adjacent blade-carrying discs in coaxial relation therewith to define the inner cylindrical surface of the working air passage between the blades. These rings are not tightly nipped between the discs and consequently air from the working air passage can creep into the annular chambers enclosed between these rings and the flanges 12a, 21a, 21b, 22a, 23a, 22b, 23b and 24a constituting the drum of the disc and drum structure. The rings 35 are prevented from rotating relatively to the discs by dowels 67.

The shaft 60 has a frusto-conical end 36 provided with a flange 37 by which it is attached to the rear end of the drum structure by the bolts 29 and the nuts 31.

Each of the blade-carrying discs is formed with a central bore 38 surrounded by a thickened hub portion. A tubular member 39 having an outwardly-directed flange 40 at its forward end and an inwardly-directed flange 41 at its rearward end is interposed between the blade-carrying discs 12 and 21, the flange 40 being secured to the discs 11 and 12 and to the spigot 13 by the bolts 16 and the flange 41 being secured to the disc 21 by nuts 43 and bolts 44 which pass through holes 45 in the flange 41 and through aligning holes 46 in the thickened hub portion of the disc 21 at a lesser radius than the bolts 16.

The tubular member 39 strengthens the forward end of the rotor and forms part of means for resisting deflection of the discs bounding separate chambers in the rotor under the action of unbalanced endwise pressure load on the discs as will hereinafter be fully described. The tubular member 39 also serves as part of a passage means or duct system for conveying air compressed in the compressor of which the rotor is to form a part to a labyrinth seal (not shown) associated with the bearing 14, where the air is used for oil sealing and cooling purposes. The duct system further comprise a tubular member 47 fitted in the bores 38 of the discs 21 and 22, a tubular member 68 fitted in the bores 38 of the discs 22 and 23 and three equally spaced tubes 52 extending radially from hollow bosses 50 provided on the tubular member 68 through holes 54 in the flange 23a to ports 69 in the ring 35 constituting the inner boundary of the working air passage between the fourth and fifth rows of blades. The tubular member 68 is closed at its rearward end so that air under pressure from between the fourth and fifth rows of blades is constrained to pass inwardly through the tubes 52 and then forwardly through the tubular members 68, 47 and 39 to the space within the axial extensions 11b and 12b of the discs 11 and 12. From here the air passes out through openings 55 in the flange of the spigot 13 to the labyrinth structure (not shown). It will be seen that this duct system divides the space within the drum structure into four separate chambers each of which is partly bounded by one or more of the discs and partly bounded by the flanges constituting the drum structure. More specifically, these chambers are firstly 70, bounded by the discs 12 and 21 and the flanges 12a and 21a, secondly 71, bounded by the discs 21 and 22 and the flanges 21b and 22a, thirdly 72, bounded by the discs 22 and 23 and the flanges 22b and 23a, and fourthly 73 bounded by the disc 23 and the flanges 23b and 24a. This last chamber is in communication through the central openings 38 of the discs 24 and 25 with the hollow interior of the shaft 60.

Considering the chambers 70, 71 and 72, if these were completely airtight, the pressure in them would depend only on the running temperature, so that the direction and extent of the pressures acting axially upon the discs

could be foreseen with reasonable accuracy. In practice however the facing joints between the parts are not completely airtight and the pressures in these chambers will therefore depend upon whether leakage occurs through the joints between the flange parts constituting the drum structure or through the joints between the discs and the tubular members forming the air duct. It is thus quite possible, for example, to have the pressure in the chamber 71 substantially equal to that between the third and fourth blade rows under one running condition and equal to that between the fourth and fifth blade rows under another running condition. Such a difference would substantially alter the endwise loadings on the discs 21 and 22.

To avoid this indeterminate state of affairs passage means are provided from each of the chambers 70, 71, 72 and 73 through the drum structure constituted by the flanges 12a, 21a, 21b, 22a, 22b, 23a, 23b and 24a to the working air passage of the compressor. In the construction shown in the drawings these passages means take the form of shallow flat-bottomed slots 74 cut in the abutment faces of the flanges, at the interfaces 61, 62, 63 and 64, there being for example three such slots equally distributed around the abutment face of each flange. The slots in the opposed faces are in alignment with one another as shown in FIGURE 3 to form elongated holes. These slots also provide a convenient way of facilitating the separation of the discs during dismantling of the rotor for overhaul by the driving in of wedge-shaped tools, the fact that the slots are opposite one another and flat bottomed enabling this to be done with minimum danger of damaging the abutment faces of the flanges. To enable such tools to be inserted, holes 75 are provided in the rings 35 opposite each of the slots 74. As already mentioned, the rings 35 are not normally so tightly fitting as to prevent all flow of air from the working air passage to the surface of the drum and thence through the slots 74, but nevertheless the holes 75 ensure that such communication is maintained.

The existence of the slots 74 ensures that the pressures in the chambers 70, 71, 72 and 73 will be graded in accordance with the stage by stage rise of pressure through the compressor and consequently the unbalanced endwise pressure loading on the discs 21, 22 and 23 is always towards the forward end of the rotor. The tubular members 47 and 68 are provided at each end with shoulders 49 which bear against the sides of the hub portions of the discs 21, 22 and 23 and consequently the unbalanced endwise pressure loads on the discs 22 and 23 are transmitted to the disc 21. The combined endwise load from all these discs is then transmitted through the tubular member 39, the hub portions of the discs 11 and 12 and the spigot 13 to the ball bearing 14 which acts as a combined journal and thrust bearing. Deflection of the discs 21, 22 and 23 under the action of unbalanced endwise pressure load is therefore resisted by the members 68, 47, 39, 11b, 12b and the spigot 13, which members act as a strut supporting the centres of the discs 21, 22 and 23 from the front compressor bearing.

Slots similar to those shown at 74 may also be provided in the abutment faces of the discs 24 and 25 and of a labyrinth seal member 76 to facilitate separation of these parts. Such slots admit to the chamber 73 supplies of air from between the sixth and seventh blade rows and from the outlet of the compressor but the pressure in the chamber 73 is not necessarily raised since air is drawn off from this chamber from the rear end of the shaft 60 for cooling the turbine part of the rotor.

I claim:

A rotor drum for a multi-stage axial flow compressor comprising a plurality of axially spaced discs having opposed axial extending portions engaging each other, pairs of adjacent discs and axially opposed portions defining closed chambers, said portions defining the outer periph-

ery of each of the closed chambers of a plurality of successive closed chambers, an annular ring of blades carried by each of the said discs on the periphery thereof, a venting passage from each of said chambers through said portions communicating each of said chambers with the flow stream between the downstream and upstream faces of each pair of adjacent rings of blades, one of said blade-carrying discs being at the low pressure end of the rotor, the chamber between said low pressure blade-carrying disc and the next higher blade-carrying disc being the lowest pressure chamber and successive chambers toward the higher pressure end of the rotor being progressively higher pressure chambers, said blade-carrying discs having central apertures therein, tubular members defining the inner walls of said successive closed chambers and disposed along the axis of the rotor in the lowest pressure chamber and in the succession of higher pressure chambers, each tubular member having an axially directed abutment face at each end engaging corresponding abutment faces around said central apertures in the blade-carrying discs, the tubular members

together forming a part of a continuous passage from the low pressure end of the rotor drum, the periphery of the drum at one of the high pressure stages having a conduit communicating the flow stream at that stage with the continuous passage.
